UNITED STATES PATENT OFFICE.

LAWRENCE A. BURCH, OF JAMESTOWN, NEW YORK.

TOOL HANDLE.

Application filed March 28, 1923. Serial No. 628,330.

To all whom it may concern:

Be it known that I, LAWRENCE A. BURCH, a citizen of the United States, residing at 30 Falconer Street, Jamestown, in the county of Chautauqua and State of New York, have invented certain new and useful Improvements in Tool Handles, of which the following, taken in connection with the accompanying drawings, is a specification.

10 This invention relates to an improvement in tool handles and particularly in one of the socketed type adapted to receive interchangeably a plurality of different blades.

Tool handles of this general form are well 15 known but it has been found they are open to the objection that it is impossible to hammer on the end of the handle without splitting the wood grip. In many cases, however, where a tool is used it is necessary, 20 in order to start it, to pound on the end of the handle and if this be done manually the hand will soon become sore and tender.

The primary object of this invention is 25 to provide a tool handle through the center of which extends a bolt which bears against the end of the blade so that any blow applied on the end of the handle will be transmitted directly to the blade and will not injure the wood grip in any way.

30 A further object of the invention is to provide in a tool handle of this type a threaded bolt by which the socket is firmly forced into position and by which any looseness in the wood grip, due to drying of the 35 wood, can be easily taken up.

40 A further object of this invention is to provide a socket for removable blades with a pocket which will co-act with an element in the shank of the blade and yieldingly holding the latter in position.

Other objects will appear from the following description taken in connection with the drawing which forms a part thereof and in which—

45 Figure 1 is a sectional view of a tool handle embodying this invention and equipped with a removable blade.

50 Fig. 2 is a cross section through the blade holding socket showing particularly the manner in which the blade is held in position.

Fig. 3 is a top view of the tool handle showing the means by which the assembling bolt is turned.

55 Referring to the drawings the reference numeral 10 is used to designate a tool handle

in accordance with this invention and comprising a wood grip 11 and a socket 12 mounted at the lower end of the grip. The socket 12 has a poly-sided recess 13 in which the shank of a blade 14 rests when the parts are assembled. At the inner end of the socket is provided a cylindrical boss 15 through which a threaded passage 16 extends into the recess 13. Secured to the 65 outer side of the boss 15 is a sleeve 17 which encloses the lower end of the grip 11. The portion of the grip so enclosed is usually made smaller than the main portion of the grip so that there is provided a shoulder 70 18 which rests against the top of the sleeve.

Through the center of the handle 10 extends a bolt 19, the lower end of which is threaded into the passage 16 in the boss. The head 20 of the bolt 19 bears against the 75 top of the wood grip 11 and in the head are provided spaced openings 21 to receive a spanner. Upon tightening the bolt 19, the grip 11 is forced into the sleeve 17 until the lower end bears against the boss 15 and the 80 lower end of the bolt projects slightly into the bottom of the recess 13.

In the walls of the recess 13 is formed an annular pocket 22 and in the shank of the blade to be mounted is seated a ball 23 so located that when the parts are assembled the ball will enter the pocket 22 and tend to hold the blade in place. As shown in Fig. 2, the ball is mounted in a recess 24 opening at the side of the shank and is normally 90 impelled outwardly by means of a spring 25.

When the parts are assembled the butt of the shank of the blade 14 bears firmly against the end of the bolt 19 projecting 95 into the recess so that any blow applied at the head of the bolt will be transmitted directly to the tool and will not cause any splitting of the handle. By reason of this construction, it is possible to equip this 100 handle with a cutting blade, such as a chisel for example, as well as the customary screw driver and gimlet blades and the tool so assembled can be used in the same manner as would be a solid chisel or screw driver. 105

While one embodiment of this invention has been shown and described, I am not to be limited thereto since it is obvious that others may be made without departing from the spirit and scope of the invention as set forth in the following claim.

Having thus set forth my invention what

I claim as new and for which I desire protection by Letters Patent is:

A tool handle comprising in combination
a grip, a socket at the end of said grip
5 adapted to receive and removably hold the
shank of the blade of a tool, a boss at the
inner end of said socket bearing against the
end of said grip, means in threaded con-
nection with said boss to hold it firmly in
10 contact with said grip one end of said means
projecting through said boss so that the end

of said shank contacts therewith whereby
any blow upon the grip will be transmitted
through said means upon said shank, and a
conical sleeve enclosing said boss and the 15
lower end of said grip, said sleeve being
forced upon said grip as the socket is se-
cured upon the grip by tightening said
threaded means.

In testimony whereof I have affixed my 20
signature.

LAWRENCE A. BURCH.
